UNITED STATES PATENT OFFICE.

AMASA C. POOLE, OF BOSTON, MASSACHUSETTS.

COMBINED SOFA AND BED.

SPECIFICATION forming part of Letters Patent No. 242,364, dated May 31, 1881.

Application filed April 10, 1880. (Model.)

To all whom it may concern:

Be it known that I, AMASA C. POOLE, of Boston, in the county of Suffolk and State of Massachusetts, have invented a new and valuable Improvement in Combined Sofa and Bed; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a rear view of my improved combined sofa and bed. Fig. 2 is a sectional view of part of the bottom-frame, showing the attachment of the mattress. Figs. 3 and 4 are sectional views of parts of the ends of the bed-bottom and frame, and Fig. 5 is a transverse section of the sofa-bed.

This invention has relation to improvements in sofa-beds; and it consists in the novel arrangement and construction of the various devices employed, as will be hereinafter more fully set forth.

In the annexed drawings, the letter A designates a shallow wooden box supported upon legs *a*, and constituting a receptacle for the bed-clothing.

B indicates a strong longitudinal wooden strip, secured to the back edge of the box A; and C C', the wooden frames hinged thereto, and serving respectively to receive the bottom and back portions of the mattress D. The frames C C' are provided with springs S, the mattress resting thereon, and being secured to the said frames by means of eyes *i* on the mattress, engaging hooks *i'* on the said frame. These eyes are arranged at the middle of the thickness of the mattress, which permits it to be turned over with either side up. At the ends of both of the frames C C' are the short head-sections D' D'', hinged thereto and adjustable to raise the head. These sections are supported in the raised position by means of

the braces *a a'*, which braces are pivoted to the frames C C', extend through guides *b* on head-sections D' D'', and, extending through slots of said sections, engage with their hooked ends *d* a metallic bar, *e*, extending across said slot, as shown. The braces are provided with handles *e'*, by means of which they are disengaged from bars *e*, and the rests allowed

to swing in line with the frames C C'; or they may be disengaged simultaneously by means of a pull-cord, *f*, the ends of which are passed through perforations in the ends of said rests, carried through guides *f'* thereon, and attached to the said braces, as shown.

G indicate strong metallic braces, composed of the sections *g g'*, the former being pivoted to the latter at or at about the middle of its length, so that they may be brought in line with each other or readily bent. These sections are pivoted, the one to the box or receptacle A and the other to the frame C', and when the latter is thrown back to form a bed the end of section *g* rests upon the floor and serves as a leg to the frame C'. The section *g'* is provided with a stop hook, *h*, that limits the vibration of the back upward to the desired inclination with the bottom. The back of the sofa is held against casual backward vibration, when raised, by means of a spring-catch, *i''*, consisting of a spring, *j*, secured at one end to section *g'*, and provided with a pin, *i'''*, at its other end, that is projected through registering-perforations in both sections. This pin renders the joint of the sections rigid, and consequently locks the back against vibration. These latches are simultaneously drawn back, and the back allowed to fall by means of a pull-cord, *N*, secured at its ends to said latches, and extending through guides between the braces and similar guides above the same, (lettered respectively *n* and *n'*.)

What I claim as new, and desire to secure by Letters Patent, is—

The combination, with a sofa having a hinged back, C', of the swinging braces G, composed of sections *g g'*, pivoted together and to the back at the upper ends, the catches *i''*, consisting of springs *j* and pins *i'''*, and a single pull-cord, *N*, connected at its ends to both catches, whereby one pull disengages both catches and permits the braces to be folded, as set forth.

In testimony that I claim the above I have hereunto subscribed my name in the presence of two witnesses.

AMASA C. POOLE.
